UNITED STATES PATENT OFFICE.

MORRIS N. DRUCKER, OF CINCINNATI, OHIO.

TRUNK.

SPECIFICATION forming part of Letters Patent No. 732,058, dated June 30, 1903.

Application filed December 6, 1901. Serial No. 84,872. (No model.)

To all whom it may concern:

Be it known that I, MORRIS N. DRUCKER, a citizen of the United States of America, and a resident of Cincinnati, in the county of 5 Hamilton and State of Ohio, have invented certain new and useful Improvements in Trunks, of which the following is a specification.

The object of my invention is a trunk into 10 and from which garments are readily packed and unpacked, which has compartments for smaller articles separated from the compartment for the larger articles, and which may easily and quickly be both thrown wide open 15 to give ready access to the interior and closed compactly. This object is attained by the means described in the specification and illustrated in the accompanying drawings, in which—

20 Figure 1 is a perspective view of a trunk embodying my invention in a partially-opened position and resting upon one of its ends. Fig. 2 is a horizontal sectional view taken upon line $x-x$ of Fig. 1, the closed position of the trunk being shown in full and a partially opened position by dotted lines. Fig. 3 is a front elevation of a movable frame for compressing the garments within the large compartment of the trunk. Fig. 4 is a 25 detail view, upon an enlarged scale, of one member of the rack upon which the frame moves. Fig. 5 is a detail end view of one of the catches upon the frame. Fig. 6 is a detail perspective view of one of the fingers secured upon the side of the frame for engaging the teeth of one of the racks.

Referring to the parts, the ends a a' , the bottom a^2 , and the rear side a^3 of trunk A are of ordinary construction and secured together in the usual manner. The front of trunk A is left open except for a narrow strip a^4 , secured at one side of the opening, and to the bottom edge of this opening is hinged a swinging front B. One end of front 45 B in its closed position touches the side of strip a^4 and to the other end is secured a rearwardly-projecting flange b , which in the closed position passes over the end a , whose braces a^5 are wedge-shaped upon their ends 50 to engage flange b , and thereby facilitate the closing of front B. Upon the top of the trunk a strip a^6 , similar to strip a^4 , is secured

at one end. Swinging top C is hinged at its rear edge to rear side a^3 of the trunk and in its closed position at one end touches strip a^6 , 55 at the other end has a flange c to fit over the end a of the trunk, and upon its front edge has a flange c' to fit over the top edge of front B.

Upon the interior of the trunk and parallel 60 to rear side a^3 is a vertical partition a^7 , which extends from end to end of the trunk. Between rear side a^3 and partition a^7 are a series of drawers D for the retention of smaller articles, such as collars, cuffs, handkerchiefs, &c.

Extending forward from the partition a^7 , between ends a a' at a point near the top of the trunk and parallel to bottom a^2 , is a fixed side a^8 , which, together with ends a a' , bottom a^2 , and partition a^7 , forms a chamber a^9 in front of and transverse to the drawer compartments and open upon the front for the reception of the larger garments, such as coats, &c., which are to be suspended from 75 a sliding rod a^{10} , which slides in ways a^{11} , secured to the inner face of end a^2 of the trunk.

Upon the interior of both bottom a^2 and side a^8 within chamber a^9 are fastened two racks e e' , which engage frame E in the following manner: Frame E has upon one of its sides rigid fingers e^2 e^3 and upon the opposite side sliding spring-pressed latches e^4 e^5 . After garments have been suspended from rod a^{10} they are compressed by frame E thus: Fingers e^2 e^3 are placed in engagement with the teeth of the racks upon bottom a^2 at the distance back from the front to which it is desired to compress the garments. The other end of the frame is then pushed inward, 90 latches e^4 e^5 snapping into engagement with the successive teeth of the racks e' upon side a^8 .

In closing the trunk front B is closed first. Upon its edge is secured a curved spring- 95 clasp F, which engages a rigid finger F' , secured upon side a^8 . Upon the edges of front B are secured the members g of latches which fit into the corresponding members g' of the latches, secured near the edges of end a and top C.

In packing and unpacking the trunk it rests upon its end a' . It is seen that front B and top C are thus easily thrown wide open,

giving ready access to chamber a^9 and to drawers D, neither of which then has any obstacle in the way to impede a person in his access to said compartments.

5. What I claim is—

1. A trunk having a swinging top and a swinging front meeting each other at their free ends, a compartment of a depth equal to the depth of the trunk adjacent to the rear side of the trunk and open upon the top, drawers in said compartment, a second compartment in front of said compartment to open upon the front, and means upon the end of the second compartment for hanging garments, substantially as shown and described.

2. A trunk having a swinging top and a swinging side which meet each other at their free ends, upon the interior of the trunk a compartment adjacent to one side and a second compartment adjacent to the first compartment, a rigid finger secured upon the outside of one compartment, a spring-clasp upon one of the swinging members to engage

the rigid finger, substantially as shown and described.

3. A trunk having its top and front open, a strip secured at one end of the top and front, a swinging top and front abutting against said strips at one end and at the other having flanges to overlap the ends of the trunk, substantially as shown and described.

4. A trunk having its top and front open, a strip secured at one end of the top and front, horizontal strips with their front ends secured upon the opposite end of the trunk, a swinging front at one end abutting against the strip and at the other having a flange to engage the wedges, and a swinging top at one end abutting against the strip at the other having a flange to overlap the end of the trunk and upon its front edge a flange to overlap the swinging front, substantially as shown and described.

MORRIS N. DRUCKER.
